(57) **CLAIM**

The ornamental design for a cabinet, as shown and described.

DESCRIPTION

FIG. 1 is a rear elevational view of a cabinet showing our new design;

FIG. 2 is a front elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a bottom, rear and right side perspective view thereof; and,

(Continued)

FIG. 8 is a top, front and right side perspective view thereof. The portions of the cabinet which are illustrated by the broken lines in the drawings or inside the border thereof form no part of the claimed design.

1 Claim, 8 Drawing Sheets
